UNITED STATES PATENT OFFICE.

DAVID W. STAPP, OF PHILLIPSBURG, KANSAS.

DRAFT DEVICE.

No. 857,211.

Specification of Letters Patent.

Patented June 18, 1907.

Application filed September 14, 1906. Serial No. 334,645.

To all whom it may concern:

Be it known that I, DAVID W. STAPP, a citizen of the United States, residing at Phillipsburg, in the county of Phillips and State of Kansas, have invented a new and useful Draft Device, of which the following is a specification.

This invention relates to draft devices or draw bars such as are used in connection with 10 passenger and freight cars.

The objects of the invention are to improve and simplify the construction of such devices; furthermore, to increase their efficiency in operation and to decrease the expense attending their manufacture.

With the foregoing and other objects in view, which will appear as the description proceeds, the invention resides in the combination and arrangement of parts and in the 20 details of construction hereinafter described and claimed, it being understood that changes in the precise embodiment of invention herein disclosed can be made within the scope of the following claims without departing 25 from the spirit of the invention or sacrificing any of its advantages.

In the accompanying drawings forming part of this specification:—Figure 1 is a horizontal section, partly in elevation, through a 30 device constructed in accordance with the invention, said device being provided with a safety attachment for use on passenger cars; Fig. 2 is a transverse vertical section; Fig. 3 is a view similar to Fig. 1, showing the device 35 without the safety attachment and adapted to be used on a freight car; and Fig. 4 is a perspective view of one of the retaining members used for holding the follower plates and springs in position.

Like reference numerals indicate corresponding parts in the different figures of the drawings.

The steel draft timbers of the device of the present invention preferably comprise a top 45 plate 1 having depending webs 2 formed at their lower ends with outwardly-directed flanges 3 to which is secured a bottom plate 4 having parallel ribs 5 which fit upward into the space between the webs 2. The bottom 50 plate 4 is held against the flanges 3 by means such as the rods 6. The draw bar 7, which at its knuckle end may be of any suitable form and construction, extends into the

space between the top 1, webs 2 and bottom plate 4, said draw bar being held upward 55 against the top plate 1 by means of the ribs 5 on the bottom plate 4.

For the purpose of permitting the necessary forward and backward yielding movement of the draw bar 7, said draw bar is 60 formed with one or more transverse slots 8 which are adapted to register with similar slots 9 formed in the webs 2. Extending transversely through the slots 8 and 9 of the draw bar 7 and webs 2 is a plurality of follower plates 10, one of which is arranged at the forward end and another of which is arranged at the rear end of each set of registering slots. Interposed between each pair of follower plates 10 is a plurality of coil springs 70 11, preferably three in number.

For the purpose of preventing the coil springs 11 and follower plates 10 from working in a transverse direction out of the slots in the draw bar 7 and webs 2, two retaining 75 members 12 are employed, one of said retaining members being located on the outer side of each web 2, as shown in Figs. 1 and 3. The retaining members 12 are formed in their outer faces with grooves 13 to receive the 80 rods 6 which serve not only to prevent the outward displacement of said retaining members 12, but also to hold them against longitudinal movement. It will be obvious that by removing the rods 6 and the retaining 85 members 12, new springs and follower plates can be supplied to the draft device whenever necessary.

In order to provide an improved safety attachment for use on passenger cars to prevent the withdrawal of the draw bar 7 from the draft timbers in the case of breakage of any of the springs, the rear end of said draw bar is provided with a cross-piece 14 which projects outward through slots 15 formed in 90 the webs 2 so that if the coil springs should give way, the cross-piece would engage the forward ends of the slots 15 and prevent the complete withdrawal of the draw bar from the draft timbers.

The draw bar illustrated in Fig. 3 is intended particularly for use upon freight cars. This draw bar is the same in construction as that illustrated in Fig. 1, except that the safety attachment is omitted.

The improved device of the present inven-

tion is strong, simple, durable and inexpensive in construction as well as thoroughly efficient in operation.

What is claimed is:

- 5 1. A device of the character described comprising a slotted draft member having spaced longitudinal flanges extending laterally from opposite sides thereof, a slotted draw bar mounted in the draft member, fol-
- 10 lower plates extending through the slots of the member and draw bar, a plurality of compression springs arranged between the follower plates, retaining members arranged between the laterally extending flanges of
- 15 the draft member and engaging the ends of the follower plates, and means on the draft member engaging the retaining member for holding the latter in place.
- 20 2. A device of the character described comprising a draft member made up of a top plate having integral slotted webs formed with outwardly directed flanges, a bottom plate secured against said flanges and having ribs fitted upwardly into the space between
- 25 said webs, a slotted draw bar resting against said ribs between said webs, follower plates extending through the slots of said webs and draw bar, springs mounted between said follower plates, retaining members resting at
- 30 their inner faces against said webs, said retaining members having grooves in their outer portions, and rods extending through

1 said bottom plate, flanges, top plate and through the grooves of said retaining members.

3. A device of the character described comprising a draft member made up of a top plate having integral slotted webs formed with outwardly-directed flanges, a bottom plate secured against said flanges and having 40 ribs fitted upwardly into the space between said webs, a slotted draw bar resting against said ribs between said webs, follower plates extending through the slots of said webs and draw bar, springs mounted between said follower plates, retaining members fitted between said top plate and said flanges and resting at their inner faces against said webs, said retaining members having grooves in their outer portions, rods extending through 45 said bottom plate, flanges, top plate and through the grooves of said retaining members, and a cross piece secured to the rear end of said draw bar and extending outward through said slotted webs to act as a safety 50 attachment.

In testimony that I claim the foregoing as my own, I have hereto affixed my signature in the presence of two witnesses.

DAVID W. STAPP.
